CLAIM

The ornamental design for a work vehicle sensor device, as shown and described.

DESCRIPTION

FIG. 1 is a perspective view of a work vehicle sensor device according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed lines in FIGS. 2-5 and 7 depict environmental subject matter. The dashed lines form no part of the claimed design.
